UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR TREATING HYDROCARBON OILS.

Original application filed April 16, 1917, Serial No. 162,234. Divided and this application filed October 11, 1919, Serial No. 329,897. Renewed July 15, 1925.

To all whom it may concern:

Be it known that I, CARBON P. DUBBS, a citizen of the United States, residing in the city of Wilmette, county of Cook, and state of Illinois, have invented certain new and useful Improvements in Apparatus for Treating Hydrocarbon Oils, of which the following is a specification.

This application is a division of an original application on continuous process of treating hydrocarbon oils, filed April 16, 1917, Serial No. 162,234.

This invention relates to improvements in apparatus for treating hydrocarbon oils and refers more particularly to improvements in an apparatus for distilling and condensing hydrocarbon oils under the pressure of the generated vapors, for converting heavy hydrocarbons into lighter hydrocarbons.

Among the salient objects of the invention are to provide an apparatus in which the partially converted vapors as they rise from the stills are condensed and returned to the stills and re-subjected to the cracking reaction so as to assure of the vapors passing over being of the same specific gravity; to provide an apparatus in which the incoming fresh oil is pumped continuously through a battery of stills and subjected to increasing temperatures, the incoming fresh oil also acting to assist in the reflux condensing action; to provide an apparatus of the above character in which the oil is at all times distilled and condensed under the pressure of the generated vapors; to provide an improved apparatus of the character referred to.

In the drawings:

Fig. 1 is an end elevation of my improved apparatus suitable for carrying out the process claimed in said application filed April 16, 1917, Serial No. 162,234.

Fig. 2 is a top plan view of the same.

Fig. 3 is a side elevation of the apparatus.

Fig. 4 is a detail view of the float valve, in still 2.

Referring to the drawings, 1 designates as a whole a suitable furnace in which are mounted horizontal cylindrical stills 2, 3, 4 and 5, the stills being mounted at succeeding elevations as shown clearly in Fig. 1. The stills are connected in series by means of pipes 6, 7 and 8, these pipes 6, 7 and 8 leading from the bottom of the stills

and entering the stills about the mid-height 55 of the latter.

Mounted above each of the stills is a combined heat interchanger and reflux condenser 9, and above these condensers 9 are mounted aerial condensers 10. Each of 60 these aerial condensers is surrounded by a shell 11 provided with a plurality of trap doors 12, 12 which can be opened to provide a freer circulation of air for the condenser. The condensers 9 are connected to 65 the top of the stills 2, 3, 4 and 5 by means of pipes 13, 13 each controlled by a valve 14, the object of the valves 14 being to permit any of the stills being cut out of the circuit. The upper end of the coils 9 are 70 connected to the coils 10 by means of connections 15, which are each controlled by a valve 16. The upper ends of the pipes 10 in turn connect to a manifold 17, through branch pipes 18, the latter in turn being 75 controlled by valves 19. The manifold 17 leads to a condenser 20, which condenser comprises headers 21 and 22 connected by tubes 23 through which the vapors pass from the pipe 17. The header 22 is in turn 80 connected to a water condenser 24 seated in water tank 25, which is supplied with cold water in any suitable manner. The condenser coil 24 is connected to the receiving tank 26 by pipe 27. The receiving 85 tank 26 is provided with drawoff pipe 28, controlled by throttle valve 29. Preferably a water drawoff pipe 30 is provided, controlled by a valve 31. A gas blowoff pipe 32 is connected to the upper end of the receiving tank and controlled by throttle valve 33. The receiving tank is controlled by suitable pressure gauge 34, and liquid gauge 35.

Describing now the means of preheating 95 the incoming supply of fresh oil to be treated, a supply pipe 36 leads to any source of supply and the oil is forced by the pump 37 through pipe 38 to the chamber 39 surrounding the tubes 23. From the upper end of 100 this chamber the oil flows through pipe 40 to manifold 41. From the manifold 41 the oil is delivered through branch pipe 42 to the chamber 43 surrounding the coil 9 mounted above the still 5. From the chamber 43, the oil passes by means of branch pipe 44 back to the manifold 41. The oil 105 then passes through branch pipe 45 to the

chamber 43 surrounding the ends of the coil 9, above still 4 then through pipe 46 back to the manifold 41, then through branch pipe 47 to the next chamber 43, thence by pipe 48 back to manifold 41, thence through pipe 49 to the next chamber 43 and back by pipe 50 to delivery pipe 51, which leads to a pipe 52, extending into the still 5 mid-height of the latter. The pipe 52 extends nearly to 10 the rear of the still 5 as shown in dotted lines in Fig. 2.

I have heretofore described the manner in which the oil passes from the still 5 into still 4, thence into stills 3 and 2. In the 15 manifold 41 are interposed valves 53, 53 which are normally kept closed. In the pipes 42, 45, 47 and 49 are interposed valves 54. In the pipes 44, 46, 48 and 50 are interposed valves 55. If it is desired to cut out 20 any one of the heat interchangers 9, to prevent too great heating of the incoming fresh oil, as for example, the one above the still 4, the valves 54 and 55 local to said heat interchanger above the still 4 are closed, 25 and the corresponding valve 53 opened.

It also may be advisable to cut out one of the aerial condensers 12. This can be accomplished by closing the corresponding valves 16 and 19 and opening the valve 56 30 interposed in the by-pass pipe 57. It is desirable that a common liquid level be maintained in the lowest still 2. This is accomplished by means of a float valve 58, having a float 59, which can be adjustable as desired. The valve 58 controls the admission 35 of oil to the pipe 60. This pipe 60 is also provided with a weighted valve 61, set at the condensing operating pressure. When this pressure is reached, the valve 61 opens 40 but only sufficient liquid can escape through the pipe 60 as will be sufficient to reduce the liquid in the still 2 to the level controlled by the float valve. On the other hand, the opening of the float valve will not let any 45 liquid escape through the pipe 60 until sufficient pressure has been reached in the system to raise the valve 61. Similarly the stills 3, 4 and 5 are provided with similar floats 59', which automatically control the 50 liquid level in these stills. The pressure which is maintained at all times on the system is controlled by means of the throttle valves on the distillate receiving tank 26.

In carrying out the process the oil is 55 heated to a sufficient temperature causing it to vaporize at the operating pressure, which pressure may be from 80 to 250 pounds, the pressure and temperature varying with the oil treated. The foregoing process converts 60 a substantial percentage of the heavier hydrocarbons into gasoline-like products. It is essential at all times that a pressure be maintained on the still and condenser, 65 which pressure is produced by the generated vapors. If desired, the contents of the still

can be mechanically agitated to prevent the caking of carbon on the bottom of the retorts, but inasmuch as mechanical stirrers are well known in the art, it is not thought necessary to show it in the drawings. 70

I claim as my invention:

1. In an apparatus for distilling and condensing hydrocarbons under pressure of generated vapors, the combination with a plurality of stills, said stills being located at 75 progressively different heights, means for heating said stills each to a given temperature, a plurality of reflux condensers disposed above said stills and in communication therewith, means for feeding oil through said reflux condensers, to preheat the same and then to the stills, communications between all of said stills, valves for controlling the number of reflux condensers through 80 which the oil must pass before entrance to the stills, auxiliary condensers disposed above said reflux condensers and in communication therewith, valves for controlling by-pass communications around such auxiliary 85 condensers, outlets from said auxiliary condensers, additional condensers in communication with said outlets, a receiving tank 90 communicating with said last mentioned condensers, and means for maintaining a pressure on oil during distillation and condensation in the apparatus. 95

2. An apparatus for distilling and condensing hydrocarbons, comprising a plurality of interconnected stills, disposed in a horizontal plane, a plurality of vertical reflux condensers mounted above said stills and in communication therewith, means for heating each still to an independent temperature, means for conveying oil through said reflux condensers and then to said stills, 100 said means including pipes and valves for controlling the number of reflux condensers through which the oil must pass prior to its delivery to the stills, a plurality of vertically disposed auxiliary condensers arranged above said reflux condensers and valve controlled communications therebetween for receiving vapors from the reflux condensers, valve controlled discharge conduits leading from said auxiliary condensers to a manifold, connections with said manifold permitting vapors to be delivered directly thereto without passage through the vertical auxiliary condensers, additional condensers in communication with the manifold, 105 a tank connected therewith, and means for maintaining a vapor pressure on the oil in the systems. 110

3. An apparatus for distilling and condensing hydrocarbons comprising a plurality of stills arranged in horizontal planes and located at progressively different levels, 115 connections between said stills, means for heating each still to a given temperature, vertically disposed reflux condensers in com- 120

munication with the stills, means for feeding oil through said reflux condensers, prior to its delivery to the stills, means for controlling the number of reflux condensers 5 through which the oil must pass, other vertical condensers in communication with the reflux condensers, means for passing oil vapors from the stills through the reflux condensers and the communicating vertical condensers, a manifold communicating with the vertical condensers, and valve connections 10 between the reflux condensers and the manifold permitting the oil vapors to pass through the reflux condensers and the vertical condensers before delivery to the manifold or through the reflux condensers alone, 15 additional condensers in communication with the manifold, and a collecting receptacle in

communication with said condensers and means for maintaining a vapor pressure on the oil undergoing distillation.

4. An apparatus for distilling hydrocarbon oils comprising a still, of vertical condensers in superimposed relation to each other in communication with the still, means 25 for feeding oil through the lower of said condensers prior to its delivery to the still, means for discharging vapors from the still to said condensers, valve communications between the condensers for causing the vapors to pass through one or both of the condensers, and a manifold for receiving the vapors after passage through one or both of the condensers.

CARBON P. DUBBS.
